Des. 185,171
Patented May 12, 1959

185,171

CLEVIS PIN

Duane W. Price, Los Angeles, Calif., assignor to D. W. Price Corporation, Los Angeles, Calif., a corporation of California

Application November 14, 1958, Serial No. 53,379

Term of patent 14 years

(Cl. D54—9)

Fig. 1 is a perspective view of a clevis pin embodying my new design, the lower portion being illustrated as broken away to indicate indeterminate length;

Fig. 2 is a front elevational view thereof;

Fig. 3 is a top view thereof; and

Fig. 4 is a side elevational view thereof.

I claim:

The ornamental design for a clevis pin, substantially as shown and described.
